UNITED STATES PATENT OFFICE.

JOHN H. PLANK, OF BLOOMFIELD, IOWA.

FILE-RACK.

1,257,528.

Specification of Letters Patent. Patented Feb. 26, 1918.

Application filed January 6, 1917. Serial No. 140,961.

To all whom it may concern:

Be it known that I, JOHN H. PLANK, a citizen of the United States, residing at Bloomfield, in the county of Davis and State 5 of Iowa, have invented certain new and useful Improvements in File-Racks, of which the following is a specification.

This invention is a file rack, more particularly adapted for use in connection with 10 supporting books, envelops or papers in vertical positions, and also to provide for making subdivisions of the filed objects with suitable markings to indicate the subdivisions.

15 One object of the invention is to provide a file rack of neat appearance, simple and strong in construction, effective to perform its required function, and one that will have a low manufacturing cost.

20 The feature of the invention resides in the provision of two parallel base strips having opposing grooves therein, in which grooves slidably engage the ends of wire partition members which serve to retain any 25 alphabetical or numerical assortment of letters, files, books, or the like.

Other objects and features of the invention will be apparent in the detailed description which is to follow and which will 30 be pointed out in the appended claims.

In the drawings which illustrate the invention,—

Figure 1 is a side elevation of the file constituting the invention, parts being 35 broken away to illustrate the detailed construction thereof, and

Fig. 2 is a transverse section of Fig. 1.

Like characters denote like and corresponding parts throughout the specification 40 and drawings.

The file, constructed according to this invention, may be adapted for use in connection with book-shelves for the purpose of retaining books in upright position, or may 45 be used separate therefrom for the purpose of containing envelops or other assortment of papers.

According to the invention, two strips 1 and 2 are provided and are arranged in a 50 substantially parallel spaced relation as will be clearly seen from Fig. 2. When using the device upon shelves, book-cases, or the like, these strips may be merely secured to the shelf 4 in spaced and parallel relation 55 by screws or fastening means 3, as also shown in Fig. 2. In the event however, that

it is desired to use the invention as a portable device for desk use, the strips may be secured in spaced and parallel relation by a transverse bar 5 connecting the bars and 60 secured thereto at their opposite edges. The opposing side edges of the strips 1 and 2 have longitudinal grooves or guide-ways 6 formed therein and adapted to receive the ends 7 of the wire partition 8. These partitions 8 are preferably made of resilient wire bent upon themselves to a substantial U-formation, their free ends being extended outwardly and looped to form eyes 7 which, as before stated, are slidably received in the 70 opposing grooves 6, and are held therein by the resiliency of the wire partitions due to the bending thereof just referred to. The loop or eye portions 7 form a substantially flat base for the partitions which when engaged in the grooves hold the partitions in a vertical position. The partitions 7 are to be of substantially the same height, although, a certain number thereof are of a greater height and are coiled at their 75 vertices, as indicated by 9. These coil portions 9 preferably extend at right angles to the plane of the partition and have the convolutions thereof sufficiently spaced to permit the insertion of charactered plates 10 80 which are designed to divide the file into alphabetical or numerical divisions, for purposes which will be understood and as indicated in Fig. 1. Each of the divisions referred to may have any desired number of 85 subdividing partitions therein. A retaining strip 11 is disposed and removably secured between said parallel strips 1 and 2 and is sufficiently spaced from the grooved edges thereof as to permit a free sliding 90 movement of the partition 8, but which will, however, prevent the accidental displacement of the partitions or a removal of their ends 7 from the grooves 6. It will thus be seen by the present invention, a file 100 of novel construction is provided, having a plurality of partitions therein, that may be readily adjusted along the base of the file for the purpose of accommodating divisional assortments of varying volumes. It 105 will also be seen that by the provision and arrangement of the coils 9, an alphabetical division of the file may be obtained, and when the same is used in connection with book-shelves, this alphabetical or numerical 110 division may be easily read at a glance.

The foregoing clearly describes my inven-

tion, however, it is to be understood that certain changes may be made that do not depart from the legitimate scope of the appended claims.

5. What is claimed is:—

1. A device of the character described comprising two spaced and substantially parallel strips having grooves formed in their opposing side edges, a plurality of partitions each formed from a strand of wire bent upon itself and having its free ends looped and extended laterally from the body of the partitions, each of said looped portions being adapted to be slidably received 10 in one of said grooves, and a retaining strip disposed within the space between said first mentioned strips and spaced from the grooved edges thereof to permit a free sliding movement of the partitions, and for preventing accidental removal of the ends of 15 said partitions from said grooves.
2. A device of the character described comprising two spaced and substantially parallel strips having longitudinal grooves 20 in the opposing side edges thereof, a plurality of partitions each consisting of a strand of wire bent upon itself and having its free ends extended outwardly and laterally therefrom, each of said free ends of the parti- 25

tions being slidably received in one of said grooves, and a retaining strip disposed between said first mentioned strips and spaced therefrom to prevent the accidental removal of said ends of the partitions from said grooves.

3. A file rack, which comprises spaced parallel strips having longitudinal grooves formed in their opposing sides, a plurality of partitions, each formed of a single length of material having substantially a U-shape, 30 the free ends of the U being bent outwardly to provide supporting feet that are adapted to slide in the grooves, certain of said partitions having a helix formed in the transverse portion of the U, the limbs of such partitions being approximately parallel, and a retaining strip interposed between and spaced from the grooved strips to permit the partitions to slide freely in the grooves 35 and to prevent their accidental removal 40 from the grooves.

45 In testimony whereof I affix my signature in presence of two witnesses.

JOHN H. PLANK.
